UNITED STATES PATENT OFFICE

JOSEPH L. BARBER, OF GREELEY, COLORADO

PHOTOGRAPHIC PRINTING MACHINE

Application filed December 22, 1928. Serial No. 328,003.

The present invention relates to photographic printing machines of a type adapted for the reproduction of photographic prints from a negative and has for its principal object to provide a machine of this character in which the print is exposed with respect to the negative for a predetermined period.

A further object of the invention is to provide pneumatic time controlling means for regulating the period of exposure of the print with respect to the negative employing means for adjusting the time controlled element to regulate the period of such exposure.

A still further important object is to provide a light box arranged for subjecting the negative and the print to the rays of light within the box and produced by electric lamps and providing a circuit closer adapted to control the lamp circuit and operable by the pneumatic time control means.

An additional object is to provide an apparatus of this character in which any desired number of prints may be made from the photographic negative and upon which the photograph will be reproduced in uniform manner by reason of the exposure of the respective print for a uniform period through the time controlled element.

Other objects and advantages reside in the special construction, combination and arrangement of the various elements forming the invention as more fully hereinafter described and claimed, reference being had to the accompanying drawings forming part hereof wherein like numerals refer to like parts throughout, and in which:

Figure 1 is a top plan view of the apparatus,

Figure 2 is a vertical sectional view illustrating the platen in printing position,

Figure 3 is a similar view showing the platen in raised position,

Figure 4 is a vertical transverse sectional view taken substantially along a line 4-4 of Figure 2,

Figure 5 is a similar view taken along the line 5-5 of Figure 3,

Figure 6 is a vertical sectional view through the pneumatic time control element

taken substantially along a line 6-6 of Figure 5,

Figure 7 is a similar view through the circuit closer and operating means therefor, the view being taken along a line 7-7 of Figure 5,

Figure 8 is a plan view of the mask for the table and illustrating the print centering lugs for arranging successive portions of the print in registry with the opening in the mask.

Figure 9 is a fragmentary plan view of the table illustrating the glass window provided therein,

Figure 10 is a perspective view of one of the light diffusing frames,

Figure 11 is a fragmentary sectional view through the supporting frame for the circuit closer operating rod, taken substantially along a line 11-11 of Figure 5,

Figure 12 is a detail of the operating connection between the pneumatic time control element and the platen releasing lever,

Figure 13 is a fragmentary sectional view of the film negative clamping rail, and

Figure 14 is a vertical sectional view through the regulating dial for the feeder valve of the pneumatic time controlling element.

Referring to the drawings in detail, wherein for the purpose of illustration I have disclosed the preferred embodiment of the invention, the numeral 5 designates the light compartment of the photographic printing apparatus having its upper portion arranged to provide a work table 6, the compartment being supported in a convenient elevated position by legs 7.

The compartment 5 is preferably associated with cabinet structure 8 disposed rearwardly of the compartment and which forms a support for the rear side thereof. The front wall of the compartment is provided with a hinged door 9 providing access to the interior of the compartment within which is suitably mounted a pilot light 10 of relatively low voltage and a plurality of electric lamps 11 of a comparatively high voltage.

The pilot light 10 and lamps 11 are arranged in separate electric circuits, each hav-

ing a control switch 12 positioned at the forward lower portion of the compartment.

Immediately above the lamps 11 is arranged a plurality of light diffusing glass frames 13, each having ground glass 14 fitted therein, the frames being disposed in superposed relation and removably supported within the upper portion of the compartment in any suitable manner well known in the art.

16 In spaced relation above the frames 13 is a glass frame 15 also having a ground glass 16 fitted therein, said last named frame being fitted in an opening 17 formed in the front wall of the compartment and by means of which each of the frames 13 and 15 may be removed from the compartment.

17 The table 6 forming the top of the compartment is provided with a window 18 within 20 which is removably fitted a transparent sheet of material 19, such as clear glass and supported at its edges by spring clips 20. An upright bracket 21 is secured to the table, rearwardly of the opening, a pin 22 is supported at the upper end of the bracket 21 and disposed horizontally to provide a pivotal mounting for the ends of a U-shaped lever 23 extending forwardly above the window.

30 The parallel sections of the lever 23, adjacent their forward ends, are provided with slotted openings 24 through which a transversely disposed pin 25 is inserted for sliding movement longitudinally of the lever. 35 A bracket 26 depends from the pin 25 that is attached to the upper surface of a platen 27 adjacent the forward edge thereof.

36 The under side of the platen 27 is provided with a layer of felt 28 or similar yielding sheet material. A beading strip 29 is secured upon the upper surface of the table 6, along the rear edge of the window 18, the portion of the beading immediately adjacent the window being provided with a removable rail 30 secured in position to the beading by a set screw 31.

50 Brackets 32 extend upwardly from the rail 30 forming a pivotal mounting for the lower ends of a pair of upwardly extending rods 33, each of said rods providing a slidable mounting for a pair of arms 34 extending rearwardly from the rear edge of the platen. Expansion springs 35 are adjustably secured upon each of the rods for engaging the upper sides of the arm whereby to yieldably urge the same downwardly thereupon.

55 A bracket 36 extends forwardly from the cabinet, above the table to the forward end of which a pump cylinder 37 is pivotally attached and provided with a piston rod 38 extending outwardly from its forward end. The outer end of the piston rod is pivotally attached to a plate 39 secured to the upper surface of the platen.

65 A piston (not shown), of conventional con-

struction is operatively mounted within the cylinder 37 and each end of the cylinder is formed with air ports providing for the intake and discharge of air into the cylinder during the movement of the piston, the structure thus provided being adapted to constitute a snubber for retarding the rapid upward or downward movement of the platen.

70 A wire 40 is connected at its opposite ends to pins 41 and 42 carried respectively by the lever 23 and bracket 21 and is coiled about the pin 22 whereby to yieldably exert a lifting force upon said lever.

75 A U-shaped rod 43 is pivotally attached at its upper end to the pin 41 carried by the lever 23 and extends downwardly with its lower end pivotally connected to a link 44. The link 44 is pivotally attached at its rear end to a bracket 44 secured to the bottom portion of the cabinet and the forward end of the link is provided with a pin 46 slidably inserted in a slotted opening 47 formed longitudinally at the rear end of a foot treadle 48. The forward end of the foot treadle extends forwardly of the leg 7 and is hingedly connected to a base member 49. It will thus be apparent from an inspection of Figures 2 and 3 of the drawings that the downward movement of the foot treadle will result in the lowering of the platen into a position over the window 95

100 A reticulated frame 50 is supported upon the wall of the cabinet beneath the table 6 and upon which frame an air cylinder 51 is supported in vertical position, said cylinder having a weighted piston 52 operatively mounted therein with a piston rod 53 extending outwardly through the top of the cylinder. Air ports 54 and 55 are formed in the upper and lower ends respectively of the cylinder.

105 A discharge pipe 56 is attached to the air port 55 having a check valve 57 interposed therein and also provided with breather valve 58. The discharge of air through the breather valve is controlled through a valve adjusting rod 59 extending upwardly to the table 6 having a socket member 60 attached to its upper end. A manually operable pointer 61 extends in a horizontal position from the socket 60 and is normally urged outwardly by a spring 115 62 carried by said socket.

110 The pointer 61 is operatively associated with a dial plate 63 secured to the upper surface of the table and within which a spiral groove 64 is formed for receiving a pin 65 depending from the under side of the pointer. The dial is thus adapted for indicating the position of the pointer with respect to the breather valve, the spiral groove 64 permitting the pointer to be turned more than a single revolution and thus provide an increase in the number of adjustable positions of the valve.

115 It will be apparent from the foregoing that through the adjustment of the breather valve 120

58, the rapidity of the downward movement of the piston 52 within the cylinder will be controlled. A pair of blocks 66 are secured to the outer end of the piston rod 53 in spaced relation with respect to each other, as clearly illustrated in Figure 6 of the drawing, the lowermost of said blocks being provided with a pair of horizontally disposed oppositely extending pins 57 and the uppermost of said blocks being provided with a single pin 68 disposed parallel with respect to one of the pins of the lower block.

5 The pin 68, and one of the pins 67 are mounted for sliding movement between a 15 pair of spaced parallel vertically extending guide members 69 attached at their opposite ends to the frame 50.

One end of a snap lever 70 extends between the upper pin 68 and its associated lower pin 67, said lever extending substantially at right angles with respect to said pin in a substantially horizontal position and is pivotally mounted intermediate its ends upon a pin 71 carried by the frame 50.

25 The opposite end of the lever 70 is engageable with upper and lower stop pins 72 and 73 respectively extending outwardly in spaced relation from a circuit closer operating rod 74 mounted for sliding movement 30 upon the frame 50.

Stop pins 75 are also carried by the rod 74 for limiting the vertical movement thereof. A spring catch 76 is also carried by the frame 50 for engagement with a notch 77 35 formed in the rod for releasably securing the rod upwardly with the circuit in open position, as clearly illustrated in Figure 7 of the drawings. The circuit closer comprises a spring contact finger 77 having its free end 40 disposed for engagement by a lug 78 formed at the lower end of the rod 74 whereby to raise the finger upwardly out of contacting position with respect to a stationary contact screw 79.

45 The circuit closer is interposed in the circuit with the electric lamps 11 whereby to control the illumination thereof. The operation of the circuit closer control arm 74 is arranged for movement in an upward or circuit open position by the lever 70 upon the movement of the piston 52 into its lowermost position.

A coil spring 80 is attached at one end to the end of the lever 70 disposed in position 55 for engagement with the pins 67 and 68 and extends in a direction substantially parallel with the lever and has its opposite end attached to a portion of the frame 50. The end 60 of the spring 80 attached to the frame is disposed in a horizontal plane with the pivot pin 71 of the lever, from which it will be apparent that the spring will urge the end of the lever, to which the spring is attached, 65 either upwardly or downwardly as soon as

the lever is moved beyond its horizontal position.

It will also be appreciated that the tension of the spring is such as to snap the lever to the limit of its upward or downward movement as soon as the same passes its horizontal position.

A lifting mechanism is provided for the piston 52 and comprises a rod 81 attached at one end to the platen lifting rod 43 and with its opposite end bent angularly and inserted in a slotted opening 82 formed at one end of a lever 83.

The lever 83 is pivotally mounted intermediate its ends upon a pin 84 carried by the frame and carries a lifting member 85 at its opposite ends. The lifting member 85 is pivotally carried by the lever 83 by a pivot pin 86 disposed adjacent the upper end of said member so that the lower end of the member will normally be suspended in a vertical plane by gravitation.

One of the vertical edges of the member 85 is formed with a shoulder 87 and adapted for engagement with the pin 67 disposed at the side of the piston rod 53 opposite from the lever 70 whereby to raise the piston 52 upon a downward movement of the platen lifting rod 43 through a similar movement of the foot treadle 48. The lifting rod 43 is normally urged in upward position by a coil spring 88 connecting the rod 81 with the under side of the table 6.

The upper portion of the vertical edge of the lifting member 85, opposite from the shoulder 87, is curved, as shown at 89 and adapted during the upward movement of said member to engage a guide roller 90 for swinging the lower end of the lifting member out of engagement with the pin 67.

Accordingly after the piston has been moved into its uppermost position, the lifting member 85 will be released therefrom. The piston is then free to move downwardly at a predetermined speed depending upon the regulation of the breather valve 58.

A mask 91 is provided for positioning upon the window 18 of the light chamber, said mask being provided with an opening 92 of predetermined area depending upon the size of the negative from which the pictures are to be reproduced. A beading 93 is formed on the upper surface of the mask that extends parallel along the rear edge of the opening 92 thereof.

Stop lugs 94 are also formed on the upper surface of the mask and are arranged in a row in spaced relation with respect to each other and parallel with the beading 93, as clearly shown in Figure 8.

The rear edge of the mask is adapted to abut the beading 93 formed along the rear edge of the window 18 and the forward edge of the mask is adapted to rest upon a beading 95 recessed in the table whereby to space 120 125 130

the forward edge of the mark slightly above the table to facilitate the gripping of the edge thereof for removing or replacing the mask in position.

5 In the operation of the apparatus, the rear edge of the negative, indicated at 96, is clamped under the rail 30 and the mark 91 is then placed in position upon the table in a manner so that the negative will appear 10 through the opening 92.

10 The sheet of print paper shown by the dotted lines as at 97, in Figure 8 of the drawings, is then placed upon the mask with the rear edge of the paper abutting the beading 15 93 and one of the side edges of the paper arranged in abutting relation with the lug 94 nearest the opening 92.

15 The light switches 12 controlling the pilot light 10 and the lamps 11 are then moved into circuit closing position, the circuit for the lamp 11 however still remaining open by reason of the contact finger 77 of the circuit closer being retained out of engagement by the circuit closer operating arm 74.

20 25 The foot treadle 48 is then depressed operating to lower the platen 27 and at the same time moving the arm 74 downwardly for moving the contact finger 77 into circuit closing position. At the same time the piston 52 is moved upwardly by the lifting member 85 and is released from said member upon reaching its uppermost position.

25 30 The weight of the piston 52 then operates to lower the piston, the speed of such downward movement being controlled by the position at which the breather valve 58 has been previously set. By reason of the spaced relation between the pins 67 and 68, provided for operating the lever 70, a predetermined movement in the piston will be possible before the lever 70 has been engaged by the pin 68 and moved downwardly beyond its horizontal position.

35 40 During this interval the negative and print paper will be exposed to the light from the lamp 11 for reproducing the picture in a manner well known in the art. As soon as the lever 70 has been moved beyond its horizontal position the circuit closer operating rod 74 will be raised through the upward movement 45 of the associated end of the lever 70 for opening the circuit and extinguishing the lamps 11.

45 50 When the lamps 11 are extinguished, the operator quickly removes his foot from the treadle and spring 88 lifts rod 43 and the platen is moved upward to inoperative position.

55 60 The sheet of print paper may then be moved into its next succeeding position, determined by the stop lugs 94 for the reproduction of the photograph upon an adjacent portion of the print paper. The print paper may be of a suitable area for reproducing a row 65 of the pictures along one edge of the paper

and then by reversing the paper, a separate row of pictures may be printed along the opposite edge thereof, such rows of pictures being defined by the dotted line shown upon the print paper in Figure 8 of the drawings, each 70 indicating areas equal to the opening 92 of the mask.

75 It will be obvious from the foregoing that a large number of the photographs may be reproduced in an expeditious and uniform manner through the use of the foregoing apparatus by reason of the uniform timing of the exposure of each of the pictures.

80 It is obvious that my invention is susceptible to various changes and modifications in construction without departing from the spirit of the invention or the scope of the appended claims, and I accordingly claim all such forms of the device to which I am entitled.

85 Having thus described my invention, what I claim as new is:

1. A photographic printing machine comprising a light chamber having electric lamps mounted therein and with its top portions constituting a work table, a window in the table, means for removably securing photographic reproducing material over the window, a platen pivotally mounted upon the table for movement into and out of position upon said reproducing material, manually operable means for swinging the platen into position on the material, a switch for controlling the current to the lamp, means actuated by the platen shifting means for closing said switch and pneumatic controlled gravity actuated means for opening said switch. 90 95 100

2. A photographic printing machine comprising a light chamber having electric lamps mounted therein and with its top portion constituting a work table, a window in the table, means for removably securing photographic reproducing material over the window, a platen pivotally mounted upon the table for movement into and out of position upon said reproducing material, a switch for controlling the current to the lamps, manually operable means for closing the switch and time controlled gravity actuated means for opening the switch. 105 110 115

3. A photographic printing machine comprising a light chamber having electric lamps mounted therein and with its top portion constituting a work table, a current control switch for the lamps, a window in the table, means for removably securing photographic reproducing material over the window, a platen pivotally mounted upon the table for movement into and out of position upon said reproducing material, an air cylinder, a weighted piston operatively arranged within and adapted for gravity actuation in one direction in the air cylinder, speed control means for the piston, means operatively con- 120 125 130

necting the piston with the switch for moving the latter in one direction, a piston rod mounted on the piston and extending outwardly of the cylinder, manually operable means for moving the piston and the switch in an opposite direction and including a pivoted rod and a lifting member carried thereby and releasably engageable with said piston rod, a snap lever operatively associated 10 with the piston rod and the switch, said piston rod being adapted for limited movement in advance of said snap lever.

4. A photographic printing machine comprising a cabinet having a light chamber, the 15 top portion of which constitutes a work table, electric lamps mounted in said light chamber, a circuit control switch for said lamps mounted in the cabinet, a window in the work table, means for removably securing photographic 20 reproducing material over the window, a platen pivotally mounted upon the table for movement into and out of position upon said reproducing material, a foot operated lever connected to the platen for swinging the same 25 into position on the material, resilient means for swinging the platen away from the material, an air cylinder mounted in the cabinet, a weighted piston mounted for reciprocation in the cylinder, a rod mounted on the 30 piston and extending from the cylinder, a pin extending materially from one side of the rod, a lever pivotally mounted in the cabinet and coupled, at one end, to the foot operated platen shifting means, a lifting member pivotally mounted on the opposite end of the 35 lever and engageable with the pin on the piston rod, means for automatically disengaging the lifting member from the pin when in its raised position, a pair of spaced lugs 40 on the opposite sides of the piston rod, a switch operating lever pivotally mounted in the cabinet and having one end disposed between the spaced lugs, said switch operating lever being operatively connected with the 45 lamp control switch and speed control means for regulating the movement of the piston in one direction.

5. A photographic printing machine having in combination, a light chamber, a platen 50 for holding a print in printing position over said light chamber, means movable by the operator for moving said platen to print holding position, a lever pivoted intermediate its ends, and a spring arranged to oscillate said lever when it passes the line of said 55 spring, a time-controlled member operatively connected to said lever and means for raising said platen operating after movement of said lever by said time-controlled means.

6. A photographic printing machine having in combination, a light chamber, a platen 60 for holding a print in printing position over said light chamber, a fluid containing cylinder, a weighted plunger movable in said cylinder, means for moving said platen to

print holding position and simultaneously lifting said plunger, means for releasing said plunger for movement into said cylinder, a spring actuated lever having an end lifted simultaneously with said plunger, means on said plunger for depressing said end of said lever after a predetermined time and means for then lifting said platen.

7. The structure set forth in claim 6, a lamp in said light chamber, a switch for controlling said light, and means operated 75 upon the movement of said lever for opening and closing said switch.

8. A photographic printing machine having in combination, a light box, a platen pivoted for downwardly swinging movement to hold the print over said light box, means normally urging said platen to in-operative position, a treadle, mechanical means connecting said treadle and platen to move said platen to print holding position, a time-controlled means, means operated by said last mentioned means to set said time-controlled means upon operation of said treadle, said time-controlled means permitting operation 90 of said first mentioned means after a predetermined period.

9. A photographic printing machine having in combination, a light chamber, a platen for holding a print in printing position over 95 said light chamber, manual means including a link connected to said platen for moving said platen to print holding position, a fluid containing cylinder, a weighted plunger movable by gravity downwardly in said cylinder, a member operated by said link for raising said plunger when said piston is moved to print holding position, means for raising said platen, and means controlled by said plunger for indicating operation of said last mentioned means after a predetermined time.

10. A photographic printing machine having in combination, a light chamber, a platen for holding a print in printing position over 110 said light chamber, manual means including a link connected to said platen for moving the same to print holding position, a fluid containing cylinder, a plunger movable by gravity into said cylinder, means connected to said link for raising said plunger when said platen is moved to print holding position, a spring actuated lever raised by said plunger, a lamp in said light chamber, a switch for controlling said lamp, a bar movable vertically by said lever for closing said switch when said platen is depressed, means for raising said platen, and means on said plunger for depressing said lever, and for moving said bar and opening said switch to 115 extinguish the light in said light chamber.

11. A photographic printing machine having in combination, a light chamber, a platen for holding a print in printing position over 120 said light chamber, a treadle, mechanical 125

- means connected to the treadle and to the platen for moving said platen to print holding position, a lifting member connected to and operated by said mechanical means, a fluid containing cylinder, a weighted plunger lifted by said lifting member, means causing said lifting member to release said plunger for movement by gravity into said cylinder, means for regulating the time of descent of said plunger, means for raising said platen and mechanical means operated by the descent of said plunger for determining the time for operation of said last mentioned means.
12. A photographic printing machine having in combination, a light chamber, a platen for holding a print in printing position over said light chamber, means for moving said platen to print holding position, a time-controlled mechanism set by movement of said means, a member moved by said time-controlled mechanism when set, a lamp in said light chamber, a switch for controlling the circuit of said lamp closed by said member, and means including said time-controlled means acting after a certain period to again move said member to open said switch, and means for then moving said platen to inoperative position.
13. A photographic printing machine having in combination, a light chamber, a lamp in said light chamber, an upwardly and downwardly swinging platen for holding a print over said chamber, means actuated by the operator for depressing said platen to print holding position and simultaneously closing the circuit of said lamp, means for moving said platen to inoperative position, and time-controlled means set by operation of said first mentioned means for opening said circuit.
14. A photographic printing machine having in combination, a light chamber, a platen for holding a print in printing position over said light chamber, a lamp in said light chamber, means actuated by the operator for moving said platen to print holding position, a lifting member operated by said means, a fluid containing cylinder, a weighted plunger movable in said cylinder lifted by said lifting member, means for releasing said plunger from said lifting member to permit said plunger to descend by gravity into said cylinder, a spring-controlled lever moved to one position by said plunger, a member movable by said lever, a switch for controlling said lamp operated by said last mentioned member.
15. A photographic printing machine having in combination, a light chamber, a platen for holding a print in printing position over said light chamber, a pneumatic means comprising an air cylinder and gravity operated plunger, means adjacent the operator's position for regulating the exit of air from said cylinder and thus the movement of said plunger, means for depressing said platen, and means for lifting of said platen.
16. A photographic printing machine having in combination, a light chamber, a platen for holding a print in printing position over said light chamber, means actuated by the operator for moving said platen to print holding position including a link, a lever connected to said link, a pivoted lifting member carried by said lever, a weighted plunger, a fluid containing cylinder into which said plunger moves by gravity, means for regulating the exit of air from said cylinder, means engaged by said lifting member causing it to disengage said plunger to permit gravity movement of the latter, a spring-controlled lever having one end moved upwardly and downwardly by said plunger, and means for raising said platen operated after said end of said lever is moved downwardly by said plunger.

In testimony whereof I affix my signature.
JOSEPH L. BARBER.
